UNITED STATES PATENT OFFICE.

ARTHUR B. CLUNIES, OF ROCHESTER, NEW YORK, ASSIGNOR TO THE SILL
STOVE WORKS, OF SAME PLACE.

DESIGN FOR A FIRE-POT LINING.

SPECIFICATION forming part of **Design No. 25,890**, dated **August 4, 1896**.

Application filed June 18, 1896. Serial No. 596,084. Term of patent 14 years.

To all whom it may concern:

Be it known that I, ARTHUR B. CLUNIES, a citizen of the United States, residing at Rochester, in the county of Monroe and State of New York, have invented and produced a new and original Design for End Linings for Fire-Pots, of which the following is a specification, reference being had to the accompanying drawings thereof.

10 Figure 1 is a perspective view of my design, and Fig. 2 a plan view of the same.

The leading feature of my design consists in the shape and configuration of the article.

15 The face 1 of the article is curved laterally and tapers slightly toward the bottom, where the curve is slightly flatter, as shown particularly in Fig. 2, and the extreme lower end is cut away to produce a narrower flange 2.

The extreme upper portion is slightly shorter than the part below it, being rounded downward and outward to produce the curved part 3 at one end and also rounded outward to produce the curved shoulder 4 at the other end. On the top is provided the lug or projection 5, and below this and on the rounded face another projection 6. The edge beneath the shoulder 4 is slightly concaved at 7, above which is the abrupt shoulder 8.

What I claim is—

The design for end lining for fire-pots, substantially as herein shown and described.

ARTHUR B. CLUNIES.
